UNITED STATES PATENT OFFICE.

DAVID L. ABER, OF PITTSBURGH, PENNSYLVANIA.

SURGICAL INSTRUMENT.

1,031,314.

Specification of Letters Patent.

Patented July 2, 1912.

Application filed September 26, 1911. Serial No. 651,388.

To all whom it may concern:

Be it known that I, DAVID L. ABER, a citizen of the United States, residing at Pittsburgh, county of Allegheny, and State of Pennsylvania, have invented certain new and useful Improvements in Surgical Instruments, of which the following is a specification.

My invention relates to speculums and similar surgical instruments, which are used 10 for dilating cavities and canals both for the purpose of examination and medical treatment, and more particularly to the dilating blades comprising a part of such instruments.

15 The primary object of my invention is to provide an instrument in which the blades may be opened and closed within a cavity without danger of pinching or injuring in any way the delicate tissues and membranes 20 forming the inner walls thereof.

The invention includes a construction of 25 blade which will permit the device to be safely and easily introduced into and withdrawn from a cavity or canal when the blades are closed, as well as a blade which may be used in connection with any preferred form of speculum, or with a syringe in such a manner as to entirely surround and inclose the nozzle of the same.

30 A further object is to provide a device entirely free from cracks, crevices or rough edges which might act to retain foreign matter and prevent a perfect sterilization of the instrument.

35 The invention consists in certain novel features of construction, and in the assemblage and combination of parts, hereinafter fully described and claimed and illustrated in preferred form by the accompanying 40 drawings wherein:

Figure 1 is a side elevation of a vaginal syringe having my improved dilating blades applied thereto, the blades being shown in open position by dotted lines; Fig. 2, a side 45 elevation, on an enlarged scale, of the forward or headed end of one of the blades; Fig. 3, an inner face view of the same; Fig. 4, a central longitudinal section of two of the oppositely disposed blades in their closed position; Figs. 5, 6 and 7, cross sections of the same taken on lines 5—5, 6—6 and 7—7, respectively of Fig. 4; and Fig. 8, a front elevation of the blades, illustrating the manner in which they fit together.

55 While my improved blades may be used in connection with any form of dilating in-

strument comprising a plurality of blades and mechanism for operating the same, I have in Fig. 1 shown them in connection with a device such as is shown and described in U. S. Letters Patent No. 989,550, issued to me April 18, 1911, which device comprises four blades each of which consists of a stem like body portion A having its forward end enlarged to form a dilating head B, to be presently described, and its opposite end C extended and curved outwardly to form a handle. The blades are evenly spaced around, and pivotally mounted, at a point intermediate their length, 60 upon a supporting member 2, mounted upon a syringe nozzle 3.

The portions C of the blades are provided with inwardly projecting pivotal arms 4, the inner ends of which are pivoted to a ring 5, 65 slidably mounted upon the inwardly projecting portion 6 of nozzle 3, and a spiral spring 7, interposed between members 2 and 5 serves to hold them normally apart with the heads B of the blades closely together in 70 position to be inserted. A slight pressure upon the rear ends of two of the oppositely disposed blades will cause all of the blades to open simultaneously, as shown in dotted lines, and when the pressure is removed the 75 reflex action of spring 7 will instantly bring the blades together again, as shown in full lines.

To permit the blades to be freely inserted 80 into a cavity and opened and closed therein without danger of pinching the delicate tissues between the meeting surfaces of the blades; each of the heads B is approximately pear shaped at the point of its greatest cross-sectional area, with the tapering 85 sides slightly bulged out for a portion of their length adjacent the inner rounded edge D, to form meeting surfaces E, as shown in Figs. 2, 3 and 6. Edge D extends in a straight line approximately the length 90 of the head and is curved outwardly at its forward end and gradually merges into the broad peripheral face F, to form a blunt 95 nose G. The periphery and tapering sides of head B, continue backward in gradually 100 converging lines to meet stem A, while the inner or straight edge D is flared out abruptly at its rear end to meet said stem as shown at H.

From the foregoing it will be seen that 110 when a number of the blades are closed together the heads B will form an approxi-

mate ball of a greater diameter than the diameter of the circumference of all of the stems A, as in Fig. 7, which will permit the instrument to be easily introduced into and withdrawn from a cavity, as will be readily understood by those skilled in the art, and by reason of off set H the stems A will be spaced sufficiently apart to permit them to be used in connection with the nozzle of a spraying device.

It is characteristic of my device that the heads B, when closed, do not come into contact with each other except at a point well within their periphery adjacent inner edge 15 D, to wit surface E, with the oppositely disposed heads spaced apart and each head resting against and supported by the two heads next adjacent in a manner to hold them firmly together and in line with each 20 other, while the open spaces between the adjacent heads and inner edges D will permit the instrument to be inserted or withdrawn and opened or closed within a cavity without pinching or injuring in any way the 25 delicate tissue forming its interior surface.

I claim:

1. A surgical instrument comprising a plurality of blades provided with heads approximately pear shaped in cross section 30 and tapering to a point at one end, said heads being adapted to meet together, with the oppositely disposed heads spaced apart and each head in contact with the two next adjacent heads for a portion of its length

within its periphery adjacent its inner edge 35 and means connecting the blades to cause them to operate simultaneously.

2. A blade for surgical instruments comprising a stem like body portion provided with an enlarged head, said head being approximately pear shaped at the point of its greatest cross sectional area with the tapering sides bulged for a portion of their length adjacent the inner edge to form meeting surfaces, said inner edge being off set 45 at one end from the stem and continuing in a straight line approximately the length of the head with its opposite end curved outwardly to meet the peripheral surface of the head and form a rounded nose. 50

3. A blade for surgical instruments comprising a stem-like body portion provided with an enlarged head, said head being approximately pear-shaped in cross section with the tapering sides thereof bulged for a 55 portion of their length adjacent the inner edge to form meeting surfaces, said inner edge having one end curved outwardly to meet the peripheral surface of the head to form a rounded nose and its opposite end 60 flared outwardly to meet the stem.

In testimony whereof, I affix my signature in presence of two witnesses.

DAVID L. ABER.
